DESIGN FOR A SHOE OR SIMILAR ARTICLE

Schuyler A. Wood, Dolgeville, N. Y.

Application May 26, 1941, Serial No. 101,141

Term of patent 3½ years

To all whom it may concern:

Be it known that I, Schuyler A. Wood, a citizen of the United States, residing in Dolgeville, in Herkimer County, in the State of New York, have invented a new, original, and ornamental Design for a Shoe or Similar Article, of which the following is a specification, reference being had to the accompanying drawing, forming part thereof.

Figure 1 is a plan view of a shoe showing my new design.

Figure 2 is a side view of the shoe, partly in perspective.

The dominant features of my invention com-

prise the ornamental composition in a counterless shoe, of the symmetrical upper portions, these portions being shaped to form an open toe and being spaced apart longitudinally and centrally of the shoe, the edges of the upper portions having an edging of a contrasting color, the portions being connected by spaced ornamental triple loop elements, each carrying a simulated button in the space between the upper portions.

I claim:

The ornamental design for a shoe or similar article, substantially as shown and described.

SCHUYLER A. WOOD.
